UNITED STATES PATENT OFFICE

ARTHUR H. RYAN, OF BIRMINGHAM, ALABAMA

GARMENT-BAGGING DEVICE

Application filed March 23, 1928. Serial No. 264,093.

This invention relates to a garment bagging device such as is employed for mounting paper bags over various garments such as clothing, coats, dresses and garments to 5 protect same while being delivered or stored.

Various devices having for their object to facilitate the application of bags over garments have been designed, but up to the present time these have either been too expensive to come into general use or, such as have been of the simpler and less expensive type have not been able to meet all of the requirements of the trade.

One object of my invention is to design 15 a bagging device so that it is capable of being mounted either overhead or on the side walls of the store or room, thereby enabling it to be put where most convenient, and I provide an adjustable support by means 20 of which it can be brought to the requisite height and position relative to the ceiling or side walls.

A further object of my invention is to provide a bagging device with a rigid L-shaped 25 hanger having a swivel connection to its mounting bracket, its vertical leg forming an adjustable support from which the garment to be bagged is hung, and its lateral leg carrying guides for a pull cord for a 30 bag engaging slide which works freely, being counterbalanced by a handle on the cord.

Another object of my invention is to provide the vertical leg of the garment supporting hanger with an undercut slide guide 35 having an elongated seat through which the beg clasp on the slide works.

A further object of my invention is to provide a slide guide in the form of two telescoping members of approximate channel shape, 40 there being a set screw attachment which will lock the members at the desired adjustment and will not interfere with the free passage thereby of the bag.

A further object is to flexibly suspend the 45 slide guide from its hanger so that it is free to swing, thereby avoiding the obvious objections to a rigid guide.

A further object of my invention is to provide the hanger with a set screw engaging 50 its swivel by means of which its lateral arm

can be presented in the desired position for most convenient operation.

My invention further comprises the novel details of construction and arrangements of parts, which, in their preferred embodiment 55 only are illustrated in the accompanying drawings, in which:—

Fig. 1 is a side elevation of my bagging device shown mounted on a side wall.

Fig. 2 is a longitudinal cross-section taken 60 on the line II—II of Fig. 1.

Fig. 3 is an enlarged cross-sectional view taken on the line III—III of Fig. 1.

Similar reference numerals refer to similar parts throughout the drawings. 65

In the embodiment of my invention illustrated, I show the bagging device as mounted upon an adjustable bracket preferably formed by an outer sleeve 5 carrying a base plate 6 adapted for attachment by any suitable means to either the side wall or ceiling. A tubular member 7 telescopes in the sleeve 5 and is adapted to be locked in the desired adjustment by a set screw 8. A bracket member 9 is secured in the end of this tubular member 7 and has a flattened radially ribbed vertically disposed surface having a central opening to receive a bolt 10 by means of which a complementary bracket member 11 with a similarly ribbed face is connected 80 thereto, said bracket members being held in the desired angular adjustment by a wing nut 12 engaged on the screw bolt 10. 75

The bracket member 11 has a shouldered swivel hanger 13 which serves as a support 85 for a T-shaped hanger that comprises a vertically disposed head 14 and a horizontally disposed arm 15. The head is recessed to receive half of the swivel member 13 and a plate 16 overlying the head portion 14 and suitably bolted thereto forms a complementary socket member to receive the swivel hanger 13. A set screw 17 will engage the swivel and lock the hanger 14 in the desired 90 adjustment about the swivel. 95

The head members 14 and 16 near their lower ends have transverse registering grooves to receive a D-ring 18 which will rock therein and from this ring is freely 100 swung the adjustable garment support and

slide guide which comprises two substantially channel-shaped telescoped guide members 19 and 20, the outer member 19 having side flanges drawn inwardly over the correspondingly shaped flanges of the inner member 20 so as to interlock the members free for telescopic adjustment. In the upper end of the inner guide 19 I secure a hook 21, which engages the D-ring 18 in such manner that 10 the garment is suspended free for universal play.

The groove provided in the inner slide member 19 receives a slide 22 which works freely up and down therein as a guide and 15 this slide carries a spring clip 23 which projects from the opening in the guides and engages the paper bag or the like 24. This slide has an eye 25 for the connection to a pull cord 26 which passes upward and about 20 an idler pulley 27 journaled in a bracket 28 provided on the hanger head 14 and then about an idler 29 on a similar bracket 30 provided at the outer end of the hanger arm 15. The free end of this cord carries a handle 31 25 which is adapted to substantially counter-balance the slide 22.

In order to adjust the slide members 19 and 20, I provide a clip 32 which embraces the slide members as shown in Fig. 3, and is provided with a hole in the back which is threaded and receives a set screw 33 which passes through an aperture in the outer guide 19 and takes a bearing against the inner guide 20. Since the sides of the clip overhang the 30 sides of the outer member 19, it follows that when the set screw is run in it will force the inner sleeve 20 outwardly and clamp it between the sides of the sleeve 19, thus holding the two slide elements interlocked in any desired adjustment longitudinally of the hanger. To prevent the set screw forming an obstruction on which the paper bag might hang as it passes it, I provide a spring guide 34 which is countersunk to receive the head of 35 the set screw 33 and thus will guide the bag freely past it in both directions. A hook 35 is attached at the bottom of the inner guide 20 to receive the hook of a garment hanger 36 from which any suitable garment to be bagged is suspended.

In operation, having assembled the device in the manner described and having attached the plate 6 to the side wall or ceiling as may be desired and adjusted to the tubular member 7 to bring the hanger in the right position, the set screw 8 is applied; then the set screw 17 is loosened and the T-arm swung to the desired position and then the screw 17 is tightened. The set screw 33 is then released 55 and the slide guide members adjusted to bring the hook 35 to the desired height for the garments to be bagged, after which the set screw 33 is tightened, locking the guides in the desired adjustment. The apparatus is then 60 ready for use and customarily this is carried

out as follows. The lower end of the guide 20 is inserted through the hole in the top of the bag and the latter is slipped up into position to be engaged by the clamp 23 on the slide, after which the handle 31 is grasped and the slide is run up high enough to expose the hook 35. The garment is then hung from this hook 35 and the bag is grasped and pulled down over the garment.

The handle 31 will hold the bag and slide 75 counterbalanced at any position and it will leave the slide always free to come down with a light pull on the bag that will not necessarily disengage it from the clamp, thus bringing the clamp and slide down and leaving them in position to receive the next bag. By lifting the handle 31 at any time the slide 80 will run down by gravity to receive the bag and there is material advantage in having this counterbalanced slide, as it avoids any definite limitation as the position in which it must be run to support the bag and leaves entire freedom for adjustment according to the varying lengths of bags that may be employed.

It will be noted that my bagging device is 90 made up of light metal castings and stamping in standard shapes which enable it to be very economically produced and supplied at a reasonable cost to the trade. The flexibility of its various adjustments makes it available for use in almost any position and thus permits it being mounted where none of the present bagging devices could be installed. The device 95 is light and can be knocked down for simple packaging and inexpensive shipment.

Though I have described with great particularity the details of the embodiment of the invention herein shown, it is not to be construed that I am limited thereto, as changes in arrangement and substitution of equivalents may be made by those skilled in the art 100 without departing from the invention as defined in the appended claims.

Having thus described my invention, what 105 I claim as new and desire to secure by Letters Patent, is:

1. A garment bagging device having a support, an extensible slide guide connected to 110 said support and formed of longitudinally adjustable members, means to hold said members in adjusted positions, means to hang a garment from the guide, and a bag carrying slide freely movable along said guide.

2. A garment bagging device having a support, an extensible slide guide connected to 115 said support and formed of longitudinally adjustable members, means to hold said members in adjusted positions, means to hang a garment from the guide, a bag carrying slide freely movable along said slide, and a counterbalancing flexible operating means for the slide.

3. A garment bagging device having a support adjustable as to length and adapted 120

- for attachment to side wall or ceiling, an extensible slide guide connected to said support and formed of longitudinally adjustable members, means to hold said members in adjusted positions, means to hang a garment from the guide, and a bag carrying slide freely movable along said guide. 5 an adjustable bracket adapted for wall or ceiling attachment, a hanger having a vertical head swivelled from said bracket and a lateral arm, a slide guide suspended from said head free to swing, a slide freely movable in said guide and carrying a bag engaging element, an operating cord for the slide having guides on the hanger and carrying a counterweight for the slide, means to adjust the slide longitudinally, means to hang a garment from the lower end of the slide guide, and means to guide the bag past the slide adjusting means. 70
4. A garment bagging device having a hanger support, an extensible slide guide freely suspended from said support, means to hang a garment from said guide, and a slide movable along said guide and carrying means to engage a bag. 10 75
5. A garment bagging device having a hanger support, an extensible slide guide freely suspended from said support, means to hang a garment from said guide, a slide movable along said guide and carrying means to engage a bag, and means to operate the slide. 15 80
6. A garment bagging device according to claim 5, in which the slide is always free in the guide and counterbalanced by its operating means. 85
7. A garment bagging device comprising a bracket, a hanger swivelled on the bracket, an extensible slide guide swung freely from the hanger, a bag engaging slide freely movable along said guide, and means to hang a garment from the slide. 90
8. A garment bagging device comprising a bracket, a hanger swivelled on the bracket, an extensible slide guide swung freely from the hanger, a bag engaging slide freely movable along said guide, means to hang a garment from the slide, and flexible slide operating means having guides in said hanger. 95
9. A garment bagging device comprising a bracket, a hanger swivelled on the bracket, an extensible slide guide swung freely from the hanger, a bag engaging slide movable along said guide, means to hang a garment from the slide, and a counterbalance means flexibly connected to the slide and accessible to manipulate the slide. 100 105
10. A garment bagging device comprising channel-shaped telescoped members, means to support the guide overhead, means to hang a garment from the guide, and a slide movable in the inner member and carrying a bag engaging member opposite the opening in the channel. 110 115
11. A garment bagging device comprising channel-shaped telescoped members, means to support the guide overhead, means to hang a garment from the guide, a slide movable in the inner member and carrying a bag engaging member opposite the opening in the channel, and means to adjust the guide members comprising a clamp adapted to engage the outer side member and carrying a set screw adapted to engage the inner guide member, there being a hole for the screw in the outer guide member. 120 125
12. A garment bagging device comprising 130
